Primary Examiner — Sheryl Lane*Assistant Examiner* — Mark T. Philipp(74) *Attorney, Agent, or Firm* — Schrantz Law Firm, PLLC; Stephen D. Schrantz(57) **CLAIM**

The ornamental design for a parcel sorting device, as shown and described.

DESCRIPTION

FIG. 1 is a front perspective view of the present invention; FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing caps in broken lines. The broken lines in the drawings depict portions of the parcel sorting device that form no part of the claimed design. The parcel sorting device is shown with a symbolic break in its length. The appearance of any portion of the article between the break lines forms no part of the claimed design.
